UNITED STATES PATENT OFFICE.

JOHN PFEIFER, OF SPRINGFIELD, OHIO, ASSIGNOR TO THE MAST, FOOS & COMPANY, OF SAME PLACE.

CASH REGISTER AND RECORDER.

SPECIFICATION forming part of Letters Patent No. 628,961, dated July 18, 1899.

Application filed April 14, 1898. Serial No. 677,637. (No model.)

To all whom it may concern:

Be it known that I, JOHN PFEIFER, a citizen of the United States, residing at Springfield, in the county of Clark and State of Ohio, have 5 invented certain new and useful Improvements in Cash Registers and Recorders, of which the following is a specification.

My invention relates to improvements in cash registers and recorders; and the object 10 of my invention is to provide what might be termed a "combination cash-register and auxiliary register," the latter of which may be an autographic register.

The principal object is to provide means by 15 which when the cash-register is operated in the usual or normal way the auxiliary register is inactive, but when an unusual transaction takes place which cannot be completed upon the main register or cash-register proper 20 then the auxiliary register will be brought into operative position and the operation of the main register prevented.

I accomplish the objects by the devices shown in the accompanying drawings, in 25 which—

Figure 1 is a sectional elevation of a well-known type of machine to which my invention is shown applied. Fig. 2 is a detail view in perspective of a portion of the same. Fig. 30 3 is a longitudinal sectional view of the same with some of the parts broken away. Fig. 4 is a sectional elevation of the auxiliary register in detail. Fig. 5 is a plan view of a portion of the same, showing a slight modification. Figs. 6 and 7 are respectively perspective views of the connecting parts of the apparatus sufficient to show the manner in which the device may be applied to registers of modified or different constructions. Fig. 40 8 is a sectional elevation of my device. Figs. 4^a and 9 are detail views of my device.

Like parts are represented by the same letters of reference in the different views.

In cash-registers, generally speaking, it has 45 been common to indicate transactions of different kinds, and these may be divided into what may be termed "usual" transactions and "unusual" transactions. The usual transactions are those which are taken care of and 50 properly registered by the machine, and in

many machines the usual transactions are confined to the registration of cash sales or transactions and the unusual transactions are those which are not taken care of by the machine proper and are such as when goods are 55 sold on account, money paid out or received on account, &c. In this class of cash-registers means are provided for indicating the unusual transactions, but the transaction itself is manually recorded on a slip, which is 60 placed with the cash in the cash drawer or receptacle. In my improved construction I provide an auxiliary device, preferably in the form of an autographic register, on which these unusual transactions may be noted, and 65 this auxiliary register is so connected to the cash-register that it is normally inactive when the cash-register is operated in its usual and intended manner, while the cash-register or register proper is rendered inactive when an 70 unusual transaction is to be recorded on the auxiliary or supplementary register.

In the accompanying drawings, A represents a cash-register of a well-known type—for instance, a type shown in the United States Letters Patent No. 579,604, dated March 30, 1897, issued to me—and B represents the auxiliary or supplementary register. In Figs. 1 to 3, inclusive, I have shown a register of the said lever type in which 80 cash-keys *a*, numbered corresponding to the amounts to be registered and indicated, are arranged in connection with suitable indicating and registering devices common in the particular type of register. These cash-keys *a* are normally locked and can only be operated after a lever *b* on the outside of the casing has been moved from its normal position, the movement of this lever being adapted to accomplish the movement of 85 the necessary indicating and registering devices, the complete operation of which is described and set forth in my prior patent, No. 579,604, dated March 30, 1897. The keys are normally held locked either in their normal 90 position or depressed position by a pivoted catch *a'*, which is operated by the movement of the lever *b*, and a shaft *b'*, to which the lever is attached in the manner further explained in my said prior patent. The opera- 100

tion of this lever b also serves to open the cash-drawer and complete the registration, which will be indicated by the keys.

The auxiliary register B is placed, preferably, outside of the main casing, and its mechanism is connected to that of the main register by a rod or shaft c , which extends from one of these devices to the other and through the respective cases thereof. This auxiliary register may be of any suitable form, but preferably embodies a strip of paper which is normally rolled up on a supply-roll c' and passing over a suitable plate c^2 is attached to a winding-roll c^3 . On the rod c , within the auxiliary register, there is an arm c^4 , which carries at its outer end a pawl c^5 , which engages with a ratchet-wheel c^6 on the end of a winding-roll c^3 , the construction being such that each time the shaft c is oscillated the winding-roll is turned a portion of a revolution corresponding to the ratchet c^6 . Within the casing of the main register A the shaft c is provided with an arm d , connected at its outer end by the link d' , which is pivoted to the lower end of a lever d^2 , journaled near its middle on a rod l , which is a part of the organization of the main register. Pivoted to the top of the lever d^2 is an L-shaped lever d^3 , which has projecting from one side thereof a lug or finger d^4 , which normally rests in a notch d^5 in a laterally-moving link or bar d^6 . This link or bar d^6 is connected at one end to an arm or collar b^2 , at the point marked a^8 in Fig. 2, on the lever-shaft b' , and is pivoted at its outer end to an arm d^7 , which turns loosely on the rod or shaft l , which is in proximity to the pivoted lever d^2 . The arrangement is such that ordinarily when the shaft b' is oscillated by the movement of the lever b a corresponding movement is imparted through the link d^6 and finger d^4 to the L-shaped arm d^3 , which in turn communicates the motion through the lever d^2 , link d' , and arm d to the shaft c , causing the same to turn and impart movement to the auxiliary register. Hinged loosely on the shaft l , between the lever d^2 and the arm d^7 , is a stop-lever e , having on one side a pin or projection e' , below the notched bar d^6 . This stop-lever e projects above and normally rests on the lug or projection d^5 on the L-shaped arm d^3 and is cut away on its under side near its outer end to form a shoulder e^2 .

In this particular class of machines the cash-keys are arranged in banks representing different denominations, those marked a being of units denominations and those marked a' of tens denominations, and each bank is provided with a hinged yoke f , which projects over all the keys in that bank for the purposes of the operations of the register, these yokes being hinged to the rod l . Extending across the keys, so as to engage all of these yokes, is a bar f' , supported on suitable arms f^2 , which are also hinged on rod l , and the bar f' is provided with a plate f^3 , (see Fig. 2,) on which the downwardly-projecting

end of the L-shaped lever d^3 rests. The result of this construction is that whenever a key in any series or bank is pressed the bar f' , and through it the L-shaped arm d^3 , will be raised. The raising of this bar after the lever b has been moved downwardly until the lug d^4 is opposite the shoulder e^2 raises the lug or projection d^4 out of the notch d^5 in the bar d^6 . As in this machine the keys can only be pressed after the lever b has been drawn down to unlock the keys, the elevating of the lug or finger d^4 from the notch d^5 can take place only when this lug or finger has been moved opposite the shoulder e^2 on the stop-lever e . The result is that if a key is depressed the lug or shoulder is raised from the notch and is held against the shoulder e^2 on the stop-lever by the cash-key, so that the bar d^6 is permitted to vibrate with the lever-shaft b' without imparting motion to the L-shaped arm d^3 and through it the auxiliary registering device. Briefly stated, the result of this construction is as follows: If the lever is pulled down and allowed to return, so as to open the cash-drawer without any manipulation of the keys or consequent registration on the main register, then the paper strip in the auxiliary register is advanced a distance corresponding to the distance between the ratchets in the ratchet-wheel c^6 on the winding-reel c^3 , and if a cash-key is not depressed prior to the time that the lever starts back to its normal position then the passing of the lug d^4 under the stop-arm e will prevent the key from being operated and prevent the operating mechanism of the auxiliary register from being detached until it has completed its stroke. Inasmuch as the stop-lever is held from rising by the pin or projection e' contacting with bar d^6 , the lug or finger d^4 can be raised out of the notch only at the point when said finger is opposite the shoulder e^2 . If, however, a key is depressed before the main operating-lever starts to return to its normal position, then the lug or finger d^4 would be raised out of the notch d^5 , and, contacting with the shoulder e^2 of the stop-lever, the parts will be locked against movement, the bar d^6 being free to move back and forth while the lug or finger rests on top of the bar, and upon the next stroke of the lever downwardly the cash-key at the limit of the downward stroke will be unlocked and the cash-key depressed will be returned to its normal position, as fully set forth in my said prior patent. Thereupon the lug or finger d^4 will automatically drop into its normal position in the notch d^5 .

In the simplest form of my device the auxiliary register is formed on top, as shown in Fig. 5, the paper strip being preferably ruled in columns to denote the character of the transactions, a space c^7 being left in the upper case or cover sufficiently wide to permit the operator to write in the column desired the amount of the transaction and the name, if necessary, of the customer. After each such operation the paper is advanced

sufficiently to bring this registration under the cover, which may, if desired, be formed for a part of the way of glass, as shown at c^8 , Fig. 5, so that the last transaction will always be in sight. The glass portion may be marked, as shown, to indicate the proper columns on the strip for particular transactions. I preferably employ an auxiliary registering device, however, as shown in Fig. 4, in which there is a supplementary recording-strip c^9 , which is normally on a roll c^{10} . This strip, which I will term the "customer's strip," is arranged to pass under the cover and out through an opening c^{11} at the end of the cover and adjacent to an operative knife c^{12} , the cover below the knife being provided with an extended opening c^{14} , separated from the opening c^7 by a bar c^{15} . Under the opening c^{14} , however, and between the recording-strip and the customer's strip is a thin metallic plate c^{16} , and at the end of this plate and immediately below the opening c^7 there is a slip of carbon or transfer paper c^{17} between the customer's and recording strips. This arrangement permits a total bill or invoice to be made out on the customer's strip through the opening c^{14} and on the metallic plate c^{16} , while the totals or footings are made through the opening c^7 and appear both on the customer's strip and the recording-strip. After the transaction has been properly recorded the customer's strip is drawn out through the opening c^{11} and the invoice severed from the strip against the knife c^{12} . This knife c^{12} stands sufficiently above the opening so that the end from which the bill is severed will project far enough from the opening so as to extend over the recess c^{13} in a position to be readily seized by the operator when the strip is to be again drawn forward. In Fig. 4 the pawl c^5 is shown. It preferably consists of a flat bar having a quarter-twist near the center, so that part stands in a horizontal plane and part in a vertical. It is cut away at the free end, as shown in Fig. 4^a, to form a shoulder c^{18} and an extended finger c^{19} . The shoulder c^{18} engages the teeth of the ratchet-wheel c^6 , while the finger extends outwardly at the side of the ratchet-wheel. Immediately above this pawl c^5 is a pivoted spring-pressed pawl c^{20} , which normally engages the same tooth of the ratchet-wheel that is engaged by the pawl c^5 when at rest. This spring-pressed pawl serves the double purpose of holding the actuating-pawl c^5 into engagement with the teeth of the ratchet and also prevents a backward movement of the winding-roll. The extended finger c^{19} affords means for raising both pawls simultaneously out of engagement with the ratchet-wheel when it is desired to remove the recording-strip. The supply-rolls c' and c^{10} preferably have friction-plates c^{21} , which bear against the same to prevent them moving too freely.

In Figs. 6 and 7 I have shown means for

connecting my auxiliary register or recording device to other forms of registers. For instance, in Fig. 6 a type of machine is illustrated in which the cash-keys a are normally unlocked and adapted when depressed to indicate the amount, register the same, and open the cash-drawer at one operation, as shown more fully in Letters Patent No. 312,014, issued February 10, 1895, to H. Pottin; and similar devices and machines. In machines of this kind special keys, such as indicated at a^2 , are employed to indicate the unusual transactions. In such case I form this special key so that it does not contact with a cross-bar a^3 , which is generally employed in machines of this kind for locking the keys and performing various other functions; but I connect this special key or each of these special keys a^2 to the link d' , which is pivoted to the arm d on the shaft c . In this case I extend the arm d from the pivotal point of the link d' , as shown at a^4 , and arrange a stop-lever a^5 in proximity to the same. This stop-lever is adapted to be operated by a projection a^6 on one of the arms of the cross-bar a^3 . It will be seen that if the cash-key is depressed and the registration thus effected the stop-lever a^5 will be moved over the arm d and the auxiliary register will be locked against operation. If, however, the special key is depressed, the auxiliary register will be operated, and while it is so operated the stop-lever a^5 will be locked by the end a^4 of the arm d , and thus all of the cash-keys locked through the agency of the cross-bar a^3 .

In Fig. 7 I have indicated a part of a machine in which the cash-keys are arranged in series, and the keys of each series operate upon a segment a^7 to set the machine in position for operation, and a special key a^2 is employed for opening the drawer and performing the operation of registration, which may be accomplished by the movement of the drawer. In this case I use an auxiliary connection a^8 , which is operated by a special key a^2 , and a notched vibrating bar d^6 is connected directly to this intermediate connecting part a^8 , and the L-shaped bar d^8 is connected directly to the arm d on the shaft c . I also connect to the movable segment a^7 a pivoted stop-lever a^9 , connected by a link a^{10} to the L-shaped bar d^8 . If the segment a^7 is moved, this pivoted stop-lever a^9 comes in contact with one arm of the L-shaped bar d^8 , which will be raised by a movement of the pivoted stop-lever a^9 , so as to withdraw the finger d^4 from the notch d^5 , thus throwing the auxiliary registering device out of operation and locking the same. It will be understood that the projecting arm on the L-shaped bar d^8 is turned upwardly instead of downwardly and locks against the pivoted stop-lever a^9 when said bar is raised. If a special key be operated before a cash-key is operated, then the auxiliary register will be operated and the cash-

keys will be locked by bringing the L-shaped bar d^3 under the stop-lever a^9 , and thus prevent the movement of the segment a^7 .

I have only shown in Figs. 6 and 7 such parts of the main registering device as are necessary to show the connections; but as these types of machines are well known and instances are shown more fully in Letters Patent No. 325,260, issued September 1, 1885, to Walter H. Maxwell, and in Letters Patent No. 312,014, issued February 10, 1895, to H. Pottin, it is thought that the operation will be readily understood. It is obvious that similar connections may be made with any of the well-known machines on the market, so that whenever the main register is operated in the usual manner the auxiliary register will be inactive, and whenever the main register is to be operated in an unusual manner the auxiliary register will be thrown into operative position.

The registering mechanism which I preferably employ is illustrated in Figs. 8 and 9, the operation of which may be briefly described as follows: Arranged above each bank of cash-keys a and adjacent to the ends thereof is a graduated segment g , which is hung on the main shaft b' by arms g' , as shown in Fig. 1, said segment being normally held by a projection g^2 on the hinged yoke f . When a cash-key is depressed, the projection g^2 will be disengaged from the graduated segment g , allowing said segment to swing until it contacts with the key depressed. This, through the connections g^3 and g^4 , will move the rack g^5 a corresponding distance, this rack g^5 being adapted to engage with the lever-pinion g^6 , which is connected to the register g^7 , and will thus operate the register to correspond with the key depressed, the said lever-pinion being brought into engagement with the rack at the proper time by mechanism connected with the lever g^8 , as fully described in my said former patent.

It is believed that from the above description the operation of the device will be clearly understood without any further description thereof.

Having thus described my invention, I claim—

1. In a cash-register a main register for registering usual transactions, an auxiliary register for registering unusual transactions, an operating connection from said main register to said auxiliary register and means substantially as described for preventing the operation of the auxiliary register when the said main register is operated in the usual manner and automatically connecting said auxiliary and main registers after the main register has been operated.

2. In a cash-register, a main register having a series of cash-keys for registering usual transactions, an auxiliary register for registering unusual transactions normally connected with said main register, an operative connection from said main register to said

auxiliary register and means substantially as described controlled by the operation of said cash-key for holding connected said main register and auxiliary register until one of the cash-keys is operated and preventing the operation of the auxiliary register when said main register is operated.

3. In a cash-register a main register for registering usual transactions, an auxiliary register for registering unusual transactions, a single connecting-shaft extending from the main register to the auxiliary register, and means connected to said shaft for preventing the operation of the auxiliary register whenever said main register is operated in the usual manner, substantially as specified.

4. In a cash-register, a main register for registering usual transactions, an auxiliary register for registering unusual transactions, operating connections from said main register to the auxiliary register, and means controlled by the operation of the main register for disconnecting the auxiliary register from the main register whenever said main register is operated and means for preventing the operation of the auxiliary register when disconnected from the main register.

5. The combination with a cash-register, cash-keys and an auxiliary recording device normally in connection with said register, means within said register for operating said recording device and means controlled by cash-keys substantially as described, for holding said recording device in an inactive position when said registering device is operated and adapted to cause the auxiliary recording device to be connected to the register after said registering device has been operated, substantially as specified.

6. The combination with a cash-register, cash-keys, and an auxiliary recording device having a recording-strip, means within said cash-register for operating the recording-strip and advancing said strip a given distance when the cash-receptacle is unlocked without operating the cash-key and means for preventing the operation of said strip when the cash-key is operated and automatically connecting the auxiliary recording device with the register when the cash-key is returned to its normal position.

7. In a cash-register a main register having a series of cash-keys adapted when operated to cause said register to indicate the amount designated by said keys, an operating-shaft and connecting devices in said register for performing or indicating an operation independent of said cash-keys, an auxiliary register connected to said main register and means for disconnecting the auxiliary register from the main register when the cash-key is depressed, but adapted to prevent the disconnection of the auxiliary register until the said operating-shaft has been moved and the cash-key depressed, substantially as specified.

8. The combination with a winding-roll of a pivoted pawl, a ratchet-wheel with which

said pawl engages said pawl being provided with a flat surface having an extended finger and a spring-actuated holding-pawl, bearing against said actuated pawl, said pawls being each adapted to simultaneously engage the same tooth of the ratchet-wheel, substantially as specified.

9. In a recording device a recording-strip, and a supplementary or customer's strip, a supply-roll and a winding-roll for said winding-strip, and a supply-roll for said auxiliary strip, a recording-plate over which said strips run, and a separating-plate over said recording-plate between said recording and auxiliary strips, an opening through the case of said recording device having a knife for severing said auxiliary strip, and a depression in said casing adjacent to said knife, substantially as specified.
10. The combination with a cash-register having a series of cash-keys, of an auxiliary recording device normally connected therewith having a recording-strip, means within said cash-register for operating the register

and also operating the recording-strip when the cash-receptacle is unlocked without operating the cash-key, means for preventing the operation of said strip when the cash-key is operated, and means for preventing the operation of the cash-key, after the operation of said strip is begun, substantially as specified.

11. The combination with a register of a recording device connected thereto, a connection between said register and recording device, means for operating said recording device by the operation of said register when a cash-key is not depressed, said recorder being disconnected by the operation of a cash-key in said register and being locked against disconnection until a cash-key is operated.

In testimony whereof I have hereunto set my hand this 14th day of February, A. D. 1898.

JOHN PFEIFER.
